UNITED STATES PATENT OFFICE.

LEO SONDEREGGER, OF NEW YORK, N. Y., ASSIGNOR OF ONE-HALF TO WILLIAM MEYER,
OF NEW YORK, N. Y.

WINDOW-CLEANER.

1,137,546.

Specification of Letters Patent. Patented Apr. 27, 1915.

Application filed July 14, 1914. Serial No. 850,905.

To all whom it may concern:

Be it known that I, LEO SONDEREGGER, a citizen of the United States, and a resident of the city of New York, Crotona Park, borough of the Bronx, in the county of Bronx and State of New York, have invented a new and Improved Window-Cleaner, of which the following is a full, clear, and exact description.

10 The invention relates to window cleaners, such as shown and described in the Letters Patent of the United States, No. 1,104,565 granted to me on July 21, 1914.

15 The object of the present invention is to provide a new and improved window cleaner arranged to permit the user to conveniently attach the cleaner to or remove it from the window sill, and to allow of simultaneously cleaning both the inner and outer faces of 20 the window pane with any desired pressure of the wipers against the faces of the window pane as required.

25 In order to accomplish the desired result the window cleaner is provided with a main frame detachably connected with a permanent fixture on the window sill to allow of placing the window cleaner in position on the window or removing it therefrom after cleaning the same. Use is also made of inner and outer wiper arms mounted to swing transversely on side bars of the main frame, means for moving the wiper arms in unison on imparting a swinging motion to the inner arm, wipers held on the free ends of the 30 wiper arms and manually controlled means connected with the outer wiper arm for positively setting the latter for its wiper to press with more or less force against the outer face of the window pane.

35 40 A practical embodiment of the invention is represented in the accompanying drawings forming a part of this specification, in which similar characters of reference indicate corresponding parts in all the views.

45 Figure 1 is an elevation of the window cleaner as applied; Fig. 2 is an enlarged side elevation of the same; Fig. 3 is a sectional plan view of the same on the line 3—3 of Fig. 2; Fig. 4 is an enlarged cross section of 50 one of the wipers, the section being on the line 4—4 of Fig. 2; Fig. 5 is a similar cross section of one of the wipers, the section being taken on the line 5—5 of Fig. 2; Fig. 6 is an enlarged cross section of the window 55 cleaner on the line 6—6 of Fig. 3 and show-

ing the wipers out of contact with the faces of the window pane; Fig. 7 is a similar view of the same with the wipers in contact with the faces of the window pane; Fig. 8 is an enlarged rear side elevation of the window cleaner with the wiper arms omitted and parts in section; Fig. 9 is a cross section of the window cleaner and showing more particularly the connection of the main frame with the bearing and the connection 60 of the latter with the permanent fixture on the window sill; Fig. 10 is a perspective view of the window sill fixture; and Fig. 11 is a perspective view of the bearing on which the main frame is mounted to swing.

65 The main frame A of the window cleaner consists of an inner bar A' and an outer bar A², the bars being rigidly connected at one end by a cross bar A³ provided at the under side with lugs A⁴, A⁵ (see Fig. 9), of which the lug A⁴ is provided with a trunnion A⁶ journaled in a side arm B' of a bearing B, having another side arm B² adapted to be engaged by a bolt C slidably transversely in the lug A⁵. The bearing B is provided with 70 a base B¹ having a polygonal socket B⁴ adapted to engage a similarly shaped post or projection D¹ rising from the post D² of a fixture D fastened by screws, nails or other fastening devices to the sill E of the window 75 E, as plainly indicated in, Fig. 1, the fixture D being located a short distance outward out of the path of the lower sash E' of the window, so that the said sash E' can be closed without interference with the permanent fixture. The post D¹ is provided with 80 a reduced top D³, through which is adapted to be passed a cotter pin D⁴ for securely locking the bearing B in position on the fixture D. By the arrangement described the 85 main frame A, on withdrawing the bolt C, can be readily disconnected from the bearing B, and the latter, on withdrawing the pin D⁴, can be readily detached from the permanent fixture D. The bolt C and the trunnion A⁶ are in axial alinement to permit of 90 swinging the main frame A up or down.

95 The outer or free ends of the side bars A', A² of the main frame A are mounted to turn on transversely extending pivots F and F' provided with longitudinally extending pivots F², F³, on which are fulcrumed wiper arms G, G' to swing in a transverse direction on the pivots F², F³. The upper or outer 100 ends of the wiper arms G, G' are provided 105

110

with wipers H, H' adapted to engage the inner and outer faces of the window pane E² of the upper or lower sash.

in order to impart a sidewise swinging motion to the outer wiper arm G' on imparting a sidewise swinging motion to the inner wiper arm G, the following arrangement is made: On the pivots F' and F² are held forks I, I' straddling the wiper arms G, G' and being pivotally connected by links I², I' with crank arms J', J² held on the ends of a transverse crank shaft J journaled in suitable bearings arranged on the cross bar A³ of the main frame A. The forks I and I' permit of a limited transverse swinging movement of the wiper arms G, G' without disengaging the wiper arms from the forks I and I'. It will be noticed that when a sidewise swinging motion is given by the operator to the wiper arm G then a like swinging motion is given to the outer wiper arm G' by the connection just described so that both faces of the window pane E² are simultaneously wiped or cleaned by the wipers H and H' when the window cleaner is in use. The wiper arm G is swung transversely toward the window pane by the operator having hold of the said wiper arm to press the wiper H with the desired force into contact with the inner face of the window pane E².

In order to press the wiper H' with the desired force against the outer face of the window pane E², the following arrangement is made: On the pivot F' intermediate the fork I' and the pivotal end of the arm G' is arranged a face cam K provided with two ratchet wheels K' and K², the teeth of which extend in opposite directions as indicated in Fig. 8. The ratchet wheels K', K² are adapted to be engaged by the terminals K³, K⁴ of a double pawl K⁵ fulcrumed at K⁶ on the outer bar A² of the main frame A. The pawl K⁵ is provided with an extension K' connected by a link L with the arm L' of a crank shaft L² journaled in the side bars A', A² of the main frame A adjacent the cross bar A³. The inner end of the crank shaft L² is provided with a crank 50 L³ under the control of the operator to permit the latter to turn the crank shaft L² with a view to swinging the double pawl K⁵ from a normal inactive position, as shown in Fig. 8, into engagement with either of the ratchet wheels K', K² according to the direction in which the handle L³ is turned at the time. When the double pawl K⁵ engages the ratchet wheel K² and a sidewise swinging motion is given to the arms G, G' 60 then the cam K is turned in the direction of the arrow a' (see Fig. 8) and when the double pawl K⁵ is moved into engagement with the ratchet wheel K' and a swinging motion is given to the wiper arms G, G' then the cam K is turned in the inverse di-

rection of the arrow a'. From the foregoing it will be seen that by the arrangement described the cam K can be turned so as to swing the wiper arm G' either toward or from the window pane E² with a view to engage the wiper H' with more or less force with the outer face of the window pane E², or to move the wiper H' far enough outward away from the window pane, to allow convenient removal of the cleaner from the window, or to place it in position on another window (see Fig. 6).

It is understood that when the face cam K is in the position shown in Fig. 6 the wiper arm G' is held in its outermost position, and when the cam K is turned in either direction as described above then the cam K imparts an inward swinging motion to the wiper arm G' to press the arm G' with more or less force in contact with the outer face of the window pane E².

The wipers H and H' are alike in construction and each consists essentially of a metal plate H² to the face of which is secured a wiping pad H³ of a suitable material. The back of each plate H² is provided with a bearing H⁴ in which is mounted a disk N to which is secured the leaf O' of a hinge O having its other leaf O² mounted to turn in a pivot O³ held on an angular bracket G² forming part of the free end of the corresponding wiper arm G or G'. By the arrangement described each wiper H is connected by universal joint with the corresponding wiper arm G to allow the pad H³ to readily assume a desired position on the face of the window pane E² to wipe the same on imparting a corresponding movement to the wiper arms G, G', it being understood that the wipers H and H' can readily pass into the corners of the window pane to insure a thorough cleaning of the entire faces of the pane (see Fig. 1).

In order to cause the outer wiper arm H' to reach the corners or sides of the window pane it is desirable to increase the stroke of the wiper arm G' relative to the stroke given by the operator to the wiper arm G. For this purpose the throw of the crank arm J² relative to the link I³ is increased by shifting the pivot I⁴ in a vertical slot J³ in the crank arm J² by the use of a cam lever P fulcrumed on the outer face of the crank arm J².

The operation is as follows: In using the device the fixtures D are permanently secured to the window sills of a building, and when it is desired to clean one of the windows the operator raises the lower sash and then places the bearing B in position on the corresponding fixture D and then connects the cross bar A³ of the main frame A with the bearing B by engaging the trunnion A⁶ with the arm B' and sliding the bolt C into engagement with the arm B². The window

cleaner is now in position on the window with the bar A' and the wiper arm G with its wiper H on the inside of the sash, and the bar A'', the wiper arm G' and wiper H' on the outside of the sash. The operator 5 can now swing the wiper arm G over toward the window pane to engage the wiper H with the inner face of the window pane E', and the operator on turning the crank arm 10 L³ causes an inner swinging of the wiper arm G' to engage the wiper H' with the outer face of the window pane E' and with the desired force. When this has been done the operator turns the handle L³ to move 15 the double pawl K⁵ into inactive position so that the wiper H' remains in engagement with the outer face of the window pane until the latter has been cleaned. The operator now takes hold with the right hand of the 20 wiper arm G and with the left hand of the link I² or the bar A' to swing the frame up and down and to swing the wiper arm G sidewise to cause the wiper H to wipe the inner face of the pane E'. As the other 25 wiper arm G' and its wiper H' are actuated from the wiper arm G it is evident that the outer face of the window pane E' is wiped or cleaned by the wiper H'. The operator by being able to swing the main frame A up 30 and down and to swing the wiper arms G and G' sidewise can readily reach every portion of the inner and outer face of the window pane with the wipers H and H' to evenly clean the same.

35 Having thus described my invention, I claim as new and desire to secure by Letters Patent:

1. A window cleaner, comprising a sill member adapted to be fixed on a window 40 sill, a bearing slidably engaging the said sill member, a frame mounted to swing up and down on the said bearing and provided with an inner bar and an outer bar, wiper arms mounted to swing transversely on the 45 said bars, and wipers held on the said wiper arms.

2. A window cleaner, comprising a sill member adapted to be fixed on a window sill, a bearing slidably engaging the said 50 sill member, a frame mounted to swing up and down on the said bearing and provided with an inner bar and an outer bar, wiper arms mounted to swing transversely on the said bars, wipers held on the said wiper 55 arms, and means for imparting a swinging movement to the outer wiper arm on imparting a swinging motion to the inner wiper arm.

3. A window cleaner, comprising a frame 60 adapted to swing up and down and provided with an inner bar and an outer bar, inner and outer wiper arms mounted to swing transversely on the free ends of the said bars, wipers held on the said wiper 65 arms, and manually controlled adjusting

means for setting the outer wiper arm to press its wiper with more or less force against the outer face of the window pane.

4. A window cleaner, comprising a frame adapted to swing up and down and provided 70 with an inner bar and an outer bar, inner and outer wiper arms mounted to swing transversely on the free ends of the said bars, wipers held on the said wiper arms, connecting means connecting the said wiper 75 arms with each other for imparting a swinging motion to the outer wiper arm on imparting a swinging motion to the inner wiper arm, and manually controlled adjusting means for setting the wiper arm to press its 80 wiper with more or less force against the outer face of the window pane.

5. A window cleaner, comprising a frame adapted to swing up and down and provided 85 with an inner bar and an outer bar, inner and outer wiper arms mounted to swing transversely on the free ends of the said bars, wipers held on the said wiper arms, connecting means connecting the said wiper 90 arms with each other for imparting a swinging motion to the outer wiper arm on imparting a swinging motion to the inner wiper arm, manually controlled adjusting means for setting the outer wiper arm to press its 95 wiper with more or less force against the outer face of the window pane, and means for varying the throw of the outer wiper arm relative to the inner wiper arm.

6. A window cleaner, comprising a frame 100 having side bars and a cross bar connecting the side bars with each other at one end, a bearing for the said frame to swing up and down, wiper arms mounted to swing transversely on the free ends of the said frame 105 side bars, wipers on the free ends of the said wiper arms, a transverse shaft journaled on the said frame cross bar and provided with crank arms, and links connecting the said 110 crank arms with the said wiper arms.

7. A window cleaner, comprising a frame having side bars and a cross bar connecting the side bars with each other at one end, a bearing for the said frame to swing up and down, wiper arms mounted to swing transversely on the free ends of the said frame 115 side bars, wipers on the free ends of the said wiper arms, a transverse shaft journaled on the said frame cross bar and provided with crank arms, and links connecting the said crank arms with the said wiper arms, the connection between the crank and the link for the outer wiper arm being adjustable to impart a longer stroke to the outer wiper arm relative to the movement 120 given to the inner wiper arm.

8. A window cleaner, comprising a frame having side bars and a cross bar connecting the side bars with each other at one end, a bearing for the said frame to swing up and 130

down, wiper arms mounted to swing transversely on the free ends of the said frame side bars, wipers on the free ends of the said wiper arms, a transverse shaft journaled on the said frame cross bar and provided with crank arms, links connecting the said crank arms with the said wiper arms, and adjusting means at the pivotal end of the outer wiper arm for setting the latter transversely to move its wiper with more or less force into engagement with the window pane.

9. A window cleaner, comprising a frame having side bars and a cross bar connecting the side bars with each other at one end, a bearing for the said frame to swing up and down, wiper arms mounted to swing transversely on the free ends of the said frame side bars, wipers on the free ends of the said wiper arms, a transverse shaft journaled on the said frame cross bar and provided with crank arms, links connecting the said crank arms with the said wiper arms, a cam on the pivotal connection between the outer wiper arm and the outer frame bar, and a manually controlled device for turning the said cam.

10. A window cleaner, comprising a frame having side bars and a cross bar connecting the side bars with each other at one end, a bearing for the said frame to swing up and down, wiper arms mounted to swing transversely on the free ends of the said frame side bars, wipers on the free ends of the said wiper arms, a transverse shaft journaled on the said frame cross bar and provided with crank arms, links connecting the said crank

arms with the said wiper arms, a face cam mounted to turn loosely on the pivot of the outer wiper arm, ratchet wheels turning with the face cam and having their teeth arranged in opposite directions, a double pawl adapted to engage either of the said ratchet wheels, a transverse crank shaft journaled on the frame, and a link connecting the said crank shaft with the said pawl.

40

45

11. A window cleaner provided with a wiper arm, a wiper plate having integral bent guides forming a bearing, a disk mounted within said lugs and adapted to turn on said wiper plate, and a horizontal and vertical hinge connection between said disk and the wiper arm.

50

12. A window cleaner provided with a wiper arm, a wiper having a bearing at its back, a disk engaging the said bearing, a hinge having one of its leaves attached to the said disk, and a pivot connecting the other hinge leaf with the said wiper arm.

13. A window cleaner provided with a fixed sill member having a polygonal post, a bearing having a socket fitting the said post, a frame having a fixed and a movable trunnion engaging the said bearing, and wiping arms mounted on the said frame.

55

In testimony whereof I have signed my name to this specification in the presence of two subscribing witnesses.
